DRIVE FOR FUEL PUMPS FOR COMBUSTION POWER ENGINES

Heinrich Becker, Augsburg, Germany, assignor
to Maschinenfabrik Augsburg-Nürnberg A. G.,
Augsburg, Germany, a corporation of Germany

Application December 17, 1930, Serial No. 502,886
In Germany December 29, 1929

4 Claims. (Cl. 123—139)

This invention relates to internal combustion engines, and more particularly to fuel supply means therefor.

One of the principal objects of the invention 5 is the provision of a fuel feeding means for internal combustion engines in which the fuel pump is operated by a cam mounted directly on the crank shaft of the engine.

Another object of the invention is the provision 10 of a multi-cylinder internal combustion engine each cylinder having a fuel valve operated by a mechanism which feeds fuel to the fuel valve of an adjacent cylinder.

Other objects and advantages of the invention 15 will be apparent from the following description, the appended claims and the accompanying drawing, in which:

Fig. 1 is a section of an engine having a fuel 20 pump drive embodying the present invention;

Figs. 2 and 3 are front views of a portion of the 25 engine, shown partly in section, illustrating the two positions of the cam operated lever;

Fig. 4 is a sectional view of a part of the engine 30 showing a modified form of construction; and

Fig. 5 is a top plan view of a portion of the 35 engine shown in Fig. 4.

Referring more particularly to the drawing by reference letters, Fig. 1 shows a portion of an internal combustion engine, having any suitable number of cylinders in which are pistons operably connected to the customary crank shaft. The engine herein shown is of the two-cycle type adapted to operate on the fuel injection principle. Engines of this type heretofore have been provided with fuel pumping means driven usually from a separate fuel pump shaft, but in accordance with the present invention the fuel pumps are driven directly from the crank shaft of the engine thus providing a very simple and light-weight construction. As shown the fuel pump *a* is mounted on a housing *b* preferably supported on the outside of the cylinder, a fuel lead pipe *c* extending from the fuel pump to the injection nozzle *d* of the engine cylinder. The fuel pump *a* is provided with a plunger which is connected to a push-rod *k* and driven by lever mechanism operated by a cam plate *f* secured to the crank arm of the crank shaft. The cam plate *f* operates a lever *h* which is provided with a roll *g* engaging the cam plate, the lever *h* being loosely carried by a shaft *i* and connected to a link *j*, the upper end of which is pivotally connected to the bottom of the push-rod *k*. The latter operates in a bore *l* in the housing support *b* and is provided with a flange *n* engaged by a spring *m*

in the housing so that the roll *g* will be maintained in engagement with the cam *f*. The cam plate *f* is secured to the crank arm by screws *e* which pass through annular slots in the cam plate so that the latter may be adjusted in the direction of its movement. It will thus be apparent that the fuel is supplied to an engine cylinder by a fuel pump which is driven from the crank arm associated with that particular cylinder so that the fuel injection will take place when the piston is 10 near the upper end of its stroke.

For engines adapted to operate in reverse directions, a second cam *f'* is provided in addition to the cam *f*. The roll *g* of the cam lever *h* may be moved into engagement with either of these 15 cams depending upon the direction of rotation desired, by longitudinal movement of the shaft *i*. Before moving the shaft *i* longitudinally the roll *g* is lifted from the cam. For this purpose a jaw *o* is keyed on the shaft *i* so as to cooperate with 20 a similar jaw *p* provided on the hub of the lever *h*. When the shaft *i* is turned, the jaw *o* engages the jaw *p* and lifts the roll *g* from the cam which it engages, after which the shaft *i* is moved longitudinally so that the roll *g* will be opposite 25 the other cam.

To adjust the roll *g* and vary the time that the injection period begins, an adjusting screw *q* is provided in the housing *r* of the engine, the screw engaging an arm *h'* rigid with the lever *h* (see Fig. 30 1). The arm *h'* is wide enough to contact with the screw *q* when lever *h* is in position to engage either of the cams *f* or *f'*. As a modified form of construction the arrangement shown in Fig. 4 may be used, in which the push-rod *k* of the fuel 35 pump plunger is provided with a part *s*. This part *s*, which is fixed to the rod *k* limits the downward movement of the rod, as it engages the top of a nut *t* which is threaded on a sleeve *u* mounted on the pump housing. By turning the nut, the 40 lower limit of movement of the push-rod *k* may be raised or lowered, and as the lower end of the push-rod is operably connected to the crank shaft in the manner shown in Fig. 1, the roll *g* of the cam lever may be adjusted relative to its co- 45 operating cam.

In engines in which the fuel is injected by means of compressed air, as shown in Figs. 4 and 5, the fuel valves *v* are preferably operated at the proper times in the cycle of operation by connections to the fuel pump mechanism. Thus the fuel valve operating means of one cylinder is adapted to feed fuel to the fuel valve of an adjacent cylinder so that the proper amount of fuel will be supplied to the fuel valve before the pre- 55

determined time of opening. The part *s* on the pump plunger *k* is shown having an arm *s* carrying a rod *w* which in turn is connected to the operating lever *x* of the fuel valve *v*. When the fuel valve is opened compressed air forces the fuel in the fuel valve into the engine cylinder. The fuel is supplied to the fuel valve before the latter opens, the fuel being forced to the fuel valve as the pump plunger of an adjacent cylinder is raised, and the fuel being retained in the valve until the valve is opened. Thus the fuel valve of each cylinder may be supplied from the pump mounted on an adjacent cylinder and operated by the crank arm associated with such adjacent cylinder.

Fig. 5 shows the fuel pump *a* of the cylinder designated by the numeral *1* arranged to supply fuel to the valve *v* of cylinder *2*, while the pump mounted on cylinder *2* supplies fuel to the valve of the cylinder *1*, the fuel pipes *y* and *z* crossing to complete the necessary connections between the fuel valve chambers of the cylinders, and the pumps.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. In an internal combustion engine, in combination, a piston and cylinder construction, a crank shaft connected to the piston, a fuel pump having a pump plunger for supplying fuel to the cylinder, a pair of cams on the crank shaft, a cam lever pivotally supported on a fixed axis and adapted to be operated by either of said cams and operably connected to the pump plunger, and means for moving said cam lever along said axis and from one of said cams to the other.

2. In an engine having a crank shaft and a fuel pump for supplying fuel to the engine cylinder, a

pair of cams on said crank shaft, a cam lever adapted to be operated by either of said cams and forming a driving means for said fuel pump, a rotatable and endwise movable shaft rotatably supporting said cam lever, and coupling means on said shaft and cam lever so that the lever may be lifted from the cam with which it is in engagement by rotational movements of said shaft and moved to a position to engage the other cam by longitudinal movement of said shaft.

3. In an internal combustion engine of the character described, engine cylinders, pistons operable therein, a crank shaft connected to said pistons, cams on said crank shaft, fuel pumps provided on the sides of said cylinders and each having a pump plunger mounted for reciprocatory movements in a direction parallel to the cylinder axis for supplying fuel to said cylinders, each fuel pump having an end thereof closely positioned adjacent a cylinder end, a fuel supply conduit connecting each pump end to a cylinder, and mounted plunger operating levers actuated by said cams in directions substantially radially of the crank shaft axis.

4. In an internal combustion engine, a piston and cylinder construction, a crank shaft having an eccentric crank pin operably connected to the piston and crank arms fixed to said crank shaft and extending to one side of the shaft axis for the support of said crank pin, a fuel injection nozzle in the cylinder, a fuel pump for supplying fuel to said injection nozzle and provided on the side of the cylinder with its upper end closely adjacent the upper end of the cylinder, a short fuel pipe connecting said pump and said nozzle, a pivoted lever for operating said fuel pump, and a segmental shaped cam fixed on the outer end of one of said crank arms and engageable with a portion of said pivoted lever to move the same in a direction substantially radially of the crank shaft to energize said fuel pump.
